UNITED STATES PATENT OFFICE.

CHARLES A. FAIRAND, OF WATERTOWN, NEW YORK.

TWO-WAY LOCK.

Application filed February 25, 1925. Serial No. 11,491.

To all whom it may concern:

Be it known that I, CHARLES A. FAIRAND, a citizen of the United States of America, of Watertown, in the county of Jefferson, in the State of New York, have invented new and useful Improvements in Two-Way Locks, of which the following, taken in connection with the accompanying drawings, is a full, clear, and exact description.

10 This invention relates to a two-way door lock and while it is particularly adapted for double doors of the swinging or sliding type it may also be used in connection with single doors either swinging or sliding and in other 15 relations where a lock of this character would be useful.

In garages and many other buildings it is desirable to provide a double lock whereby the door or doors may be locked from both 20 sides, such, for example, as the inside and outside in such manner that each lock is accessible for locking and unlocking at one side only of the doors and the main object of my present invention is to provide a double 25 lock of this character which will enable the user to unlock and open the door or doors from either side even though the doors may be locked from the opposite side.

Another object is to permit the same lock 30 to be used for single or double, hinged or sliding doors.

Other objects and uses relating to specific parts of the lock will be brought out in the following description.

35 In the drawings:

Figure 1 is a perspective view of a pair of swinging doors equipped with my improved lock.

Figure 2 is an enlarged horizontal sectional view through the lock and adjacent edges of the doors to which it is applied.

Figure 3 is a perspective view of the detached locking device.

As illustrated the lock is used in connection with a pair of swinging doors —1— and —1'— adapted to swing to and from open positions in the direction indicated by arrows —x—, Figure 2, and comprises a T-shaped plate —2— having lateral branches —3— and —4— and an intermediate branch or stem —5— disposed at substantially right angles to the branches —3— and —4— between the ends thereof for receiving and supporting a hasp member —6— which is hinged thereto at one end by a pivotal pintle —7— to swing horizontally through an arc

of substantially 180 degrees or from one extreme position as shown by full lines to its other extreme position as shown by dotted lines.

60 The lateral branches —3— and —4— of the plate —2— are adapted to overlap upon the adjacent faces of one and the same side (but in this instance the inner side) of the doors —1— and —1'— respectively at opposite sides of the meeting edges of the door while the stem or branch —5— is adapted to extend between the meeting edges and sliding beyond the outer faces of the doors when the latter are closed to permit the 70 hinged hasp —6— to swing flatwise against the adjacent face of one of the outer doors as —1'—.

75 The inner face of one of the doors as —1— and the outer face of the other door as —1'— are provided respectively with staples —8— and —8'— mounted upon suitable supporting plates —9— and —9'— which in turn are secured by screws —10— or other suitable fastening means to the adjacent faces 80 of the respective doors.

85 The staple —8— is slidable inwardly and outwardly through guide openings in the plate —9— and a recess —11— in the adjacent part of the door so as to facilitate the locking and releasing of the adjacent arm 90 clasp —4— of the plate —2—, said arm —4— being provided with a lengthwise slot —12— of just sufficient size to permit the staple —8— to pass easily therethrough.

95 Other suitable locking members as —13— may be passed through the staple —8— and against the adjacent arm —4— for locking said arm to the door as —1— and thereby holding the door in its closed position when the other door as —1'— is closed.

100 The hasp —6— is also provided with a lengthwise slot —12'— of just sufficient size to permit the passage of the staple —8'— therethrough or rather to permit the hasp to be moved to and from a position embracing said staple when the door is closed after which a suitable locking member as —13'— may be inserted through the staple and across the adjacent face of the hasp —6— to hold 105 the door in its closed position.

110 A stud —14— is slidably mounted in a socketed plate —15— on the side of the door —1'— adjacent the branch arm —3— of the plate —2— and is spring-pressed outwardly by a coil spring —16— into an opening —17— in the branch —3— for additionally

supporting the plate —2— and also affording additional locking means for the doors particularly if they are slideable instead of swinging, the outer end of the stud —14— being rounded or beveled to enable the branch —3— to ride against and depress the same when the doors are closing.

Operation.

10 Assuming now that the doors are hinged to swing open in the direction indicated by arrows —x— and are both locked inside and outside by their respective locking members —13— and —13'— and keepers —8— and —8'— then if the user entering the room from the inside wishes to unlock and open both doors it is simply necessary to remove the locking member —13— which permits the door —1— to be swung outwardly to its extreme open position after which the door —1'— with the locking member —2— and parts carried thereby may also be swung to its open position.

Assuming again that both doors are locked 25 in their closed positions from both sides, and that the user wishes to open the doors from the outside in which case it is simply necessary to remove the locking member —13'— and then to swing the hasp —6— from the position shown by full lines to the position shown by dotted lines which permits the door —1'— to be swung open after which the door —1— may also be opened.

On the other hand after the doors are hinged 35 to swing inwardly or in a direction opposite that indicated by the arrows —x— and they are both locked inside and outside and it is desired to open the doors from the inside, the locking member —13— may be withdrawn thus permitting both doors to be opened inwardly or if it is desired to open the doors inwardly from the outside the locking member —13'— may be withdrawn and the hasp —6— locked to a position substantially parallel with the stem —5— thus permitting the door —1— to be opened sufficiently to disengage its branch —3— from the stud —14— and thereby to allow both doors to be opened inwardly simultaneously.

50 If the doors are adapted to slide toward and from each other and are both locked from the inside and outside and it is desired to open them from the inside the locking member —13— may be withdrawn and the staple —8— pushed by hand into the recess —11— beyond the adjacent arm —4— of the plate —2— thus permitting either or both of the doors to be opened.

Again assuming that the doors are slideable and are both locked from the inside and that it is desired to open the doors from the outside in which case it is simply necessary

to remove the locking member —13'— and to swing the hasp —6— out of engagement with the staple —8— whereupon the hasp —6— may be used as a handle by which to force the end branch —3— of the plate —2— out of engagement with the stud —14— whereupon either or both doors may be moved laterally away from each other to 70 their open positions.

The extreme end of the branch —3— and also the end of the stud —14— are rounding in cross section to enable the branch —3— to ride upon and depress the stud —14— 75 against the action of the spring —16— into the opening —17—.

While the sliding doors are still open the arm —4— of the plate —2— may be locked from the inside in the manner previously described after which the user may pass out through the open doors and close them and lock them from the outside by means of the hasp —6— and locking member —13'— or if it is desired to lock the garage from the inside the operator may first lock the hasp —6— to the staple —8'— by means of the locking member —13'— and then after the doors are closed the staple —8— may be withdrawn outwardly through the then registering slot —12— at the arm —4— and locked by means of the member —13—.

In a similar manner the doors may be double locked from the outside or from the inside. The staples —8— and —8'— are preferably located equal distances from the meeting edges of the doors and in like manner the slots in the hasp arms —4— and —6— are arranged equal distances from the meeting edges of the door thus permitting the device to be reversed so that the arms —4— and —6— may take the place of each other in which case the stud —14— would, of course, be ineffective, but in some instances this stud —14— and its operating spring 105 —16— may be entirely dispensed with without departing from the essential features of the invention.

What I claim is:

A double door lock of the character described, comprising a T-shaped plate having its stem adapted to pass between the meeting edges of the doors and its branches adapted to overlap upon the adjacent sides of the doors, one of said branches being provided with a slot, a hasp hinged to the stem to swing to and from a position across the opposite face of one of the doors and provided with a slot, keepers on opposite faces of the doors adapted to enter the adjacent slots and locking members engaging said keepers.

In witness whereof I have hereunto set my hand this 19th day of February, 1925.

CHARLES A. FAIRAND.
